METHOD OF CUTTING OR FLAME-
MACHINING METAL

William Bryce Nicholson and Everett P. Jones,
Elizabeth, N. J., assignors to The Linde Air
Products Company, a corporation of Ohio

Application June 11, 1937, Serial No. 147,698
Renewed November 18, 1939

10 Claims. (Cl. 148—9)

This invention relates to the art of deseaming, cutting, or flame-machining metal work by directing a jet of oxidizing gas onto the same, and particularly to a method of starting such a cutting, deseaming, or flame-machining operation.

Heretofore, such operations have been started by pre-heating the metal work to an ignition temperature at the point where metal removal is to begin, and directing a jet of oxidizing gas onto the work at the point of pre-heating. After the cutting, deseaming, or flame-machining operation has begun, the pre-heat may be lessened owing to the pre-heat effect of the slag or oxidized metal that precedes, or is blown ahead of the nozzle as it is advanced over the work.

These present known methods require considerable time to initially pre-heat the metal work to an ignition temperature, and it has been customary to increase the delivery of pre-heating gas in order to reduce the pre-heat starting time, e. g., by providing the blowpipe with relatively large pre-heat orifices of much greater diameter than is necessary for continuing the operation after it has begun. Since the velocity of the pre-heat gas must be maintained above a certain limit in order to maintain flame stability and to prevent back-firing of the blowpipe, the large pre-heat orifices deliver a pre-heating gas of such volume that it impairs the efficiency of metal removal and greatly increases operating costs. Any attempt to decrease the volume of pre-heating gas after the metal removal operation has begun reduces the gas velocity and causes the pre-heat flame to become unstable and back-firing occurs.

When it is desired to remove surface metal within the boundaries of cold metal work, it becomes exceedingly difficult to sufficiently pre-heat the point where the metal removal operation is to begin. Problems of this latter nature arise in many instances, particularly in steel mills where it is desirable to employ a deseaming operation to remove cracks, fissures, and other imperfections within the surface boundaries of cold billets and other bodies consisting of oxidizable metal such as steel.

An object of this invention is to provide the most efficient and economical normal pre-heat capable of continuing a cutting, deseaming, or flame-machining operation after it has been started, and to augment the intensity of such normal pre-heat to effect the starting of such an operation within a relatively short time interval.

Another object of this invention is to substan-

tially instantaneously raise a portion of cold metal work to an ignition temperature by depositing a globule of molten metal thereon and directing a jet of oxidizing gas onto said globule.

Other objects of the invention include, the provision of a method for reducing the starting time of a cutting, deseaming, or flame-machining operation by introducing a metal fuse into the pre-heat flame in such manner that it will almost instantly be raised to the fusion temperature, and directing an oxidizing jet onto the globule of molten metal thus formed causing the same to oxidize, and forcing the globule of molten metal into intimate association with the work being effected; the provision of a method wherein the metal fuse is in such angular relation with the axis of the oxidizing jet that upon melting it will be blown towards and deposited upon the surface to be affected; and the provision of a method wherein said metal fuse is so related to the pre-heat flame that it will receive the maximum heat therefrom.

Another specific object of the invention includes the provision of a method for substantially instantaneously raising the temperature of a portion of surface metal within an area of metal work to an ignition temperature by employing a relatively low pre-heat consumption and combining with the same a jet of oxidizing gas and a globule of molten metal.

Other objects will become apparent from the hereinafter described process and apparatus in light of the accompanying drawings, in which:

Fig. 1 is an elevational view, partly in section, of a deseaming or cutting blowpipe constructed to carry out the principles of the invention;

Fig. 2 is an enlarged sectional view along line 2—2 of Fig. 1;

Fig. 3 is an elevational section along line 3—3 of Fig. 2;

Fig. 4 is an elevational view, partly in section, of a modified form of apparatus for performing the method of the invention;

Fig. 5 is a section along line 5—5 of Fig. 4;

Fig. 6 is a section along line 6—6 of Fig. 4;

Figs. 7 to 11, inclusive, are diagrammatic sketches illustrating the correct positioning of the wire in the pre-heat flames and the oxygen jet;

Fig. 12 is an elevational view, partly in section, of a further modified form of apparatus for performing the method of the invention; and

Fig. 13 is an enlarged sectional view along line 13—13 of Fig. 12.

The method of this invention comprises the

starting of a cutting, deseaming, or flame-machining operation by introducing an increment of a metal fuse, preferably in the form of cylindrical, flat, or twisted wire of ferrous metal, into a pre-heat flame, the intensity of which is sufficient to continue the operation in the most efficient and economical manner after the same has been started. The portion of metal wire so introduced into the pre-heat flame instantly melts and falls or is deposited onto the metal work at the point where metal removal is to begin. When the increment of wire introduced into the pre-heat flames reaches a semi-fluid state, a jet of oxidizing gas is directed onto the same thereby superheating and oxidizing the globule of molten metal formed by the wire fuse, and forcing it onto the metal work to be affected. The heat generated by the oxidization of the increment of hot or molten metal is readily transferred to a small area of the work beneath the same and is sufficient to raise that area of metal to the kindling temperature. Continued application of oxygen at the point where the globule is deposited, effects oxidation of the work, which may be converted into a cutting, deseaming, or flame-machining operation by moving the oxygen jet relative to the work. Continued operation is maintained by virtue of the inherent heat of the puddle formed by the fused metal work and the action of the pre-heat flames which are preferably of low intensity for more economical operation.

Care must be exercised in practicing the method of this invention to avoid incorrect deposition of the globule of molten metal on the work, otherwise the jet of oxidizing gas may dislodge the globule or blow it away from the place where metal removal is to begin. It has been found that the wire should be introduced into the pre-heat flames and the oxygen jet at such an angle that it will intersect the axial center line of the cutting oxygen stream above the surface of the work, or before its end contacts the metal work.

Referring to Figs. 7 to 9, inclusive, the angularly-arranged blowpipe nozzle N in each figure is disclosed in combination with an oxidizable and fusible metallic fuse wire W in correct angular position relatively to the heating and oxidizing jets of the nozzle. Depending on the specific construction of the nozzle N, the wire can be introduced at various angles as illustrated in Figs. 7 to 9; however, in each instance it is to be noted that before the end of the metal wire contacts the work it intersects the axial center line X of the cutting oxygen jet discharging from the central oxygen passage P of the nozzle and the wire also intersects several of the preheat flames Y.

Each oxy-acetylene pre-heat flame Y consists of three distinct cones, namely, a mixing cone in which the unburned acetylene and oxygen are mixed; an inner cone surrounding the mixing cone and in which the primary combustion of the acetylene and oxygen occurs to form carbon monoxide by the union of the carbon from the acetylene and the oxygen, and water vapor by the union of the hydrogen of the acetylene and the oxygen; and an outer mantle where complete combustion is effected. It is well known that the region of highest temperature within the pre-heat flame is at a point adjacent the tip of the inner cone. The introduction of the wire to the pre-heat flame should be at this point, provided, however, that the nozzle angle permits the introduction of the wire into the preheat flames

and the oxygen jet, preferably at such an angle that the starting rod or wire will intersect the cutting oxygen jet above the surface of the work, preferably at the axial centerline of the jet and before the rod contacts the work. Where the nozzle angle is such that the wire cannot be inserted at the most desirable point of maximum heat and still maintain the previously-described angular relation of the wire and the oxidizing gas jet, the former should be sacrificed for the latter, since the wire may be moved along substantially three-quarters of the length of the inner cone of the pre-heating flame without effecting a noticeable change in the starting pre-heat time. This procedure is possible because the normal temperature range along the inner cone length is upset by the contacting wire.

With constant fuel-gas consumption, the size of the wire introduced to the pre-heat flames directly affects the starting pre-heat time. The size of the wire, however, is limited by the stability of the wire feeding equipment, i. e., its ability to introduce and hold the wire in the specified position until the operation has been started; by the oxidizing gas stream which will blow wire of too small a diameter out of line; and by the fact that wire of too small a diameter will produce an insufficient mass of molten metal to adequately fuse a sufficiently large area of the work to begin the cut. It has been found that wires of diameters between the range of $\frac{1}{8}$ and $\frac{3}{16}$ of an inch will satisfactorily carry out the method with a cutting oxygen velocity of approximately 700 feet per second, an approximate 1 to 1 oxy-acetylene ratio, and a deseaming speed of approximately 45 feet per minute. Where other oxygen velocities are used and other values different than those specifically recited are employed, wires of varying diameter may of course be used.

The position of the pre-heat flames Y with reference to the wire is determined by the size of the wire. Referring to Figs. 10 and 11, the pre-heat flames Y should be arranged to either straddle or fall directly upon the wire depending on the position in which they will most effectively heat the wire.

One form of apparatus capable of effecting the herein-described process is disclosed in Figs. 1, 2 and 3 of the drawings. It comprises an oxy-acetylene torch T, upon which is mounted a device F near the forward portion thereof adapted to feed incremental lengths of cylindrical, flat, twisted, or otherwise formed metal wire W into the pre-heating jets delivered by the nozzle N of torch T. The feeding device F is connected to, or otherwise associated with, a manually-operable lever L adapted to open the cutting oxygen valve on the torch T and to feed an increment of wire into the pre-heat flames of said torch. In order to direct the successive increments of wire into the pre-heat flames at the proper angle and position, a guiding device G is mounted on the torch adjacent the nozzle N. This device is adapted to guide the successive increments of wire into the pre-heat flames in such a manner that they will be instantly heated to a molten state. The guide G also positions the wire increments in the stream of oxidizing gas so that the molten globules formed therefrom are oxidized and are forced onto the portion of metal work at a predetermined point where a metal removing operation is to begin.

Referring to Fig. 1 of the drawings, torch T comprises a handle 5 having a valve body 6 at 75

its rear end adapted to support oxygen and acetylene connections and to form passages and chambers for controlling the flow of the respective gases within the torch. An oxygen inlet 7, adapted to be controlled by a valve 4 (Fig. 4), is attached to the body 6 and directs the incoming oxygen into chambers within the body 6, which chambers are connected to the oxygen duct 8. For controlling the flow of oxygen to the nozzle 10 N, a valve is provided within the body 6, comprising a valve head 9 and stem 10 resiliently held in closed position by a spring 11. The valve 9 is operated by a lever L pivoted to the outside of handle 5 near its front end. A valve-operating bell-crank 13 is pivotally mounted on a pin 14 within the cylindrical handle 5. One arm of the bell-crank 13 is connected to the lever L by a link 12. For a purpose to be hereinafter described, it is desirable that the lever L be moved a certain distance independently of the bell-crank 13, and for this reason a lost-motion connection is provided between the bell-crank 13 and the lever L. As disclosed, an elongated slot 15 in the upper portion of the link 12 is adapted to cooperate with a rigidly-mounted pin 16 located at the end of one leg of the bell-crank 13.

The bell-crank 13 is provided with an abutment aligned with one end of a plunger 21, the opposite end of which is adapted to engage the valve stem 10. Thus it is seen that the valve 9 may be unseated by depressing the lever L, and upon release of said lever, spring 11 will automatically re-seat valve 9. An acetylene inlet 22, controlled by a main acetylene valve 23 is likewise attached to the body 6 and controls the flow of acetylene to a mixing throat where it is mixed with oxygen bled from the oxygen inlet 7 through by-pass 26.

The specific form of torch is not essential to the operation of the invention. The structure which has been described is only intended to show the relation between the oxygen valve-operating mechanism and the wire-feeding and guiding apparatus to be described.

The wire-feeding device F is intended to feed incremental lengths of metallic wire into the pre-heat flames issuing from the torch nozzle N in timed relation with the opening of the cutting oxygen valve 9. One form of apparatus capable of feeding the wire as required is disclosed in Figs. 1 to 3 inclusive, and is conveniently mounted on the torch T between the handle 5 and the nozzle N in position to maintain balance of the torch. The wire-feeding device F includes a wire-supporting and guiding device 36 comprising two spaced leg portions 37 and 38 integrally joined at their lower ends by a strip 39. The upper end portions of the legs 37 and 38 are provided with concave surfaces, the curvature of which corresponds to the curvature of the lower pipe 29 extending between the handle 5 and the nozzle head 32. The guiding device 36 is soldered or welded to the pipe 29 and provides a convenient support and guiding means for the metallic wire. It positions the wire with respect to the feeding device F so that gripping mechanism may effectively engage and deliver incremental lengths of the wire in front of the torch nozzle N. For the purpose of preventing excessive wear between the metallic wire and the support 36, hardened steel bushings 40 and 41 are inserted within axially aligned wire-guiding bores within the legs 37 and 38.

In accordance with the previously disclosed method, it is desirable to introduce the incre-

mental lengths of metallic wire into the pre-heat flames and the oxidizing gas jet so as to maintain a specific relation between the wire and the flames and jet. In the embodiment disclosed in Figs. 1 to 3, this has been accomplished by providing a metallic conduit 42 between the support 36 and the tip of nozzle N. The tube 42 is accurately fixed within leg 38 of the support 36 by a clamp 43. The exit of the tube 42 is accurately located with respect to the outlets of the nozzle N by a bracket 45 fixed to and depending from the torch head 32. A hardened steel guiding bushing 47 is mounted in the bracket 45 in such angular relation with respect to the nozzle N that it directs the incremental lengths of metallic wire into the pre-heat flames at a point adjacent the ends of the inner cones of such flames. The bushing 47 also directs the wire into the oxidizing jet so that it will intersect the axial centerline of said jet before the end of the wire contacts the metal work.

Feeding of incremental lengths of metallic wire past the support 36, through the tube 42, and into the pre-heat flames and oxidizing jet may be accomplished by an oscillatable gripping device. Such a device may be positioned with regard to the support so that during the clockwise portion of its oscillating movement it will grip the wire and force it along the tube 42, and will freely ride over the wire during the counter-clockwise portion of its oscillating movement.

In the embodiment of the invention shown in Figs. 1 to 3, the pivotally mounted gripping device may comprise a two part yoke 52 consisting of matched legs adapted to straddle the conduits 8, 28, 29 and 30 of torch T. The lower portion of the yoke 52 extends below and around the wire support and guiding device 36. A pivotal mounting 48 for the yoke 52 is soldered or welded to the top of the conduits 8 and 30 and it is likewise straddled by the yoke 52, supporting the same for pivotal movement on a pin 51. For effecting the incremental feeding of the metallic wire during the oscillation of the yoke 52, a gripping disc 54 is positioned within the yoke and is provided with a central aperture of slightly greater diameter than that of the wire. The disc 54 is of hardened steel construction, and the aperture therein is countersunk in only one surface so that a slight tilting movement of the disc at the beginning of the clockwise oscillation of the yoke 52 will cause the same to seize the wire and advance it toward the nozzle N. During the counter-clockwise portion of the oscillation, the countersunk aperture will permit the gripping disc 54 to freely ride over the wire.

Inasmuch as it is desirable for the gripping disc 54 to tilt slightly during its actuation, it is pivotally mounted on pins 56 within recesses 55 in opposed faces of the legs of the yoke member 52. Since the recesses 55 are provided with shoulders 50 adapted to contact the edges of the gripping disc 54 during the counter-clockwise portion of the oscillating movement of the yoke 52, they permit the disc to tilt in only one direction from the longitudinal axis of the yoke 52. These shoulders 50, therefore, aid in returning the disc to its initial position by maintaining it in position to freely slide over the wire. At the beginning of the clockwise portion of the oscillating movement of yoke 52, positive gripping of the wire by disc 54 will be insured if the disc is tilted slightly. This tilting movement of disc 54 may be effected if its lower edge is frictionally engaged by a stationary member. Positive fric-

tional engagement of the lower edge of disc 54 with a stationary member may be insured by providing a leaf spring 61 riveted to the top surface of the element 39, and so positioned that a slightly bowed portion thereof frictionally engages the lower edge of the disc 54 at the beginning of the clockwise portion of the oscillating movement of the yoke 52.

For the purpose of preventing excessive counter-clockwise pivotal movement of the gripping disc 54 about its pivot 56, when the device is not threaded with wire, a plate 49 is attached to the rear edges of the legs of yoke 52 in such manner that it overlies the recesses 55 formed in these legs. The plate 49, of course, is provided with an opening sufficient to prevent interference with the passage of the wire through the gripping disc 54.

The yoke 52 may be oscillated by any manually operable means, and in the preferred embodiment of the invention as disclosed in Figs. 1 to 3 inclusive, it is advantageous to effect this oscillation in timed relation with the operation of the cutting oxygen valve 9. For this reason, operating lever L has been constructed so that its movement will be magnified, and it is arranged so that its movement will impart oscillations of sufficient magnitude to the yoke 52. The slot and pin connection 15, 16 between the lever 13 and the link 12 permits sufficient movement of the lever L to effect the desired oscillation of yoke 52, to feed an increment of wire into the preheat flames without, however, opening valve 9.

The valve operating motion of lever L may be transmitted to the oscillatable yoke 52 by means of a rigid link 58 which has its one end pivotally connected to a boss 57 welded to the forward portion of the lever L, and its other end pivotally attached to the top portion of the yoke 52. Thus it is seen that by depressing the lever L, feeding device F will function to feed the desired increment of wire into the pre-heat flames, and upon completion of the depressing act, a slight continued operation of the feeding device and the operation of valve 9 will be effected. This slight additional feeding of wire into the pre-heat flames and oxygen jet does not affect the process; the wire is melted and blown away as waste material. A compression spring 60 is attached to the top portion of yoke 52 and also to a portion of the torch T ahead of the feeding device F for returning the feeding device, the oscillatable yoke 52, and the lever L to their initial positions, upon release of the latter.

Wire of short lengths, or wire from a reel which may be conveniently strapped to the operator's back can be fed along the torch T through the bushing 40, the aperture in gripping disc 54, the bushing 41, the tube 42, and the guiding bushing 47, to a correct position in front of the outlets of nozzle N.

A modified form of the apparatus embodying the principles of this invention is disclosed in Figs. 4 to 6. It includes a modified wire-feeding device in combination with the form of torch as disclosed in Figs. 1 to 3.

Referring specifically to Figs. 4 and 5, the torch T is provided near its forward end with a combined feeding and guiding device F' and G'. The combined feeding and guiding device extends downwardly along the torch nozzle N and in such relation with said nozzle that wire may be guided and incrementally fed into the pre-heat flames and the oxygen jet in the manner disclosed in

connection with the previously described method and the apparatus of Figs. 1 to 3.

The modified form of the apparatus shown in Figs. 4 to 6 may or may not be operated in timed relation with the operation of the oxygen valve lever L. As shown, a tiller wire 100 extends from the feeding device F' to a trigger element R fastened to the handle 5 of torch T. The location of the trigger on handle 5 is adjacent to but independent of the lever L so that it may be conveniently manipulated by the operator's hand which holds the torch.

The combined feeding and guiding device F' and G' is mounted within a housing 72, which is supported by a split clamp 70 tightly fitting around the conduits 8, 28, 29 and 30 of torch T. The housing 72 comprises two sheet metal portions 73 and 74 which are integrally joined at their lower ends by overlapping portions and screws 75. The upper extremities of the portions 73 and 74 are securely fastened to the clamp 70 by a connection including elongated slots which permit slight angular adjustment of the housing 72.

One leg 73 of the housing 72 is provided with lips 76 which form with the leg 74 a chamber within which the gripping mechanism may be located, and to which the guiding mechanism may be attached. A guiding boss 77 of hardened steel for guiding the metallic wire through the exit end of housing 72 is welded or soldered to the one lip of leg 73, and is provided with a bore 78 of slightly larger diameter than that of the metallic wire which is adapted to be fed therethrough. This boss is also provided with a bore 79 and a counter bore 80 for receiving part of the gripping mechanism to be hereinafter described. Another guiding boss 81 is attached to the lip of leg 73 which forms the entrance to housing 72, and it is likewise formed of hardened wear-resisting steel.

The gripping and propelling means of both the first and second forms of the invention are generically the same, in that each depends upon the oscillating movement of an element for propelling the wire, and upon a pivotally mounted gripping disc adapted to seize the wire during the clockwise portion of its oscillation and to release and freely slide over the wire during the counter-clockwise portion of its oscillation. The oscillatable element of the modified apparatus shown in Figs. 4 to 6 takes the form of a lever 91 mounted at the central portion of housing 72 by a pivot shaft 92. The lower end of lever 91 is pivoted to a hardened steel gripping disc 93, and the upper end of lever 91 is attached to the tiller wire 100 which is adapted to transmit oscillatory movement to said lever. For the purpose of compensating for the angularity of lever 91 during oscillation, pivotal shaft 92 is provided with a central opening adapted to slidably engage and support lever 91 thereby permitting relative movement between the lever and its pivotal support.

The wire gripping disc 93 is similar to the corresponding gripper 54 of the modification disclosed in Figs. 1 to 3 in that it is provided with an aperture 94 countersunk only in one face of the disc for permitting free movement of the disc over the wire in one direction of its movement and effecting gripping of the wire during its movement in the opposite direction. The disc 93, however, differs from gripper 54 in that a second aperture 95 is provided which is countersunk at each face of the disc. The latter aperture forms a cross-head connection with a guid-

- ing bolt 98 rigidly mounted within housing 72 by the screw threads of bore 78 within boss 71. Clockwise motion is imparted to the lever 91 by manually operable means, and counter-clockwise motion is imparted to said lever by a coiled compression spring 97 encircling bolt 98, one end of which is received within counter bore 80 of boss 71, the other end of which abuts against gripping disc 93.
10. Oscillation of lever 91 may be effected by manually operable means independent of the operation of the main oxygen valve 9. In the modified form of the invention, a trigger R is mounted on the handle 5 of torch T in position relative to the lever L so that it may be operated at will. The tiller wire 100 connects the trigger with one end of the oscillatable lever 91.

Referring to Fig. 6, a split-clamp 101 is mounted in fixed relation about handle 5 by fastening means 102. The clamp 101 is provided with a protruding boss 103 upon which is mounted a stud 104. The stud supports the trigger R and is provided with a cotter pin for maintaining the trigger thereon. The trigger comprises a circular disc having a tangentially arranged finger operating lever 108. The periphery of the disc is provided with a groove 105 in which the tiller wire is adapted to be wrapped. A pin 106, adjacent one end of the groove 105, anchors the tiller wire to the trigger element.

A further modified form of the apparatus embodying the principles of this invention is disclosed in Figs. 12 and 13. It includes still another form of wire-feeding device in combination with a somewhat different form of cutting torch from that disclosed in Figs. 1 and 4.

Referring specifically to Figs. 12 and 13, torch T' comprises a handle 110 having a body 112 at its rear end adapted to support oxygen and acetylene connections and to form passages and chambers for controlling the flow of the respective gases within the torch. An oxygen inlet 114 adapted to be controlled by a valve 115 is attached to the body 112 and directs the incoming oxygen into chambers within the body 112 and through the oxygen duct 118. For controlling the flow of oxygen through the torch T', an additional spring-closed valve (not shown) is provided in the body portion 112, including a valve-stem 116 extending outside of said body. Valve-stem 116 is adapted to be operated by hand lever L' pivoted intermediate its ends to the body portion 112. The end of lever L' adjacent to the valve-stem 116 is provided with a head 120 having an under-cut recess 122 adapted to provide a lost motion connection between the end of stem 116 and the head 120, for a purpose to be hereinafter described. The opposite end of lever L' is provided with a sliding hook 124 adapted to pass within an opening 126 formed in the handle 110 and to engage the inner wall thereof. An acetylene inlet 128 adapted to be controlled by a valve 130 is also connected to the body portion 112, and it conducts acetylene to passages and chambers within the torch T' where it is mixed with oxygen to form a combustible mixture which passes through the conduit 132. The conduits 118 and 132 are adapted to be connected with a head 134, and in the present instance it is desirable to offset the handle 110 relative to the head 134 for a purpose to be hereinafter described. The conduits 132 and 118 are therefore bent upwardly at a 45° angle from the horizontal, and after the desired offset has been accomplished they are again bent to a

horizontal position and connected with the head 134. The nozzle N is adapted to be connected with the head 134, and to direct pre-heating jets and an oxidizing stream from its end.

Referring to Fig. 12, the torch T' is provided with a combined feeding and guiding device F' and G' at its forward end. The combined feeding and guiding device extends downwardly along the torch nozzle N in a somewhat similar manner to that disclosed in Fig. 4, and in such relation with said nozzle that wire may be guided and incrementally fed into the pre-heat flames and the oxygen jet in the manner disclosed in connection with the previously described method.

The feeding and guiding device F' and G' comprises a two piece housing 138 rigidly secured to and depending from a lug 136 secured to the head 134. The housing 138 is adapted to enclose and support the wire feeding and guiding mechanism. A feeding body 140 is adapted to be secured to the lower extremity of the housing 138, and it is provided with guides 142 and 144 at the entering and exit ends of said body. Each of the guides 142 and 144 are provided with countersunk portions adapted to facilitate the passage of the wire through said body 140.

The incremental feeding of the wire into the pre-heat and oxygen streams of the torch T' is effected by an incremental rotary movement of a pair of friction wheels between which the wire W is fed. The lower friction wheel 146 is journaled in an adjusting link 148 pivoted on a pin 149 within the body portion 140. The end of link 148 opposite to that which is pivoted, is provided with an aperture adapted to cooperate with an adjusting pin 150 adjustably secured in the bottom portion of the body 140. A compression spring 152 encircles the adjusting pin 150 and resiliently urges the adjusting link 148 clockwise about its pivot. A cooperating friction wheel 154 is mounted on a shaft 156 extending between the sides of the housing 138. Both the wheels 146 and 154 are vertically aligned, and their peripheral surfaces are grooved and knurled so that they will effectively grip the wire W and feed it toward the nozzle N when the wheels are rotated.

Incremental rotary movement of the gripping wheels 154 and 146 is effected by the motion of hand lever L'. In the embodiment of the invention disclosed in Figs. 12 and 13, this has been accomplished by providing a rack and pawl mechanism adapted to be actuated by a linkage connected to the lever L'. The friction wheel 154 is provided with a ratchet 158 on each side thereof. A pivot shaft 160 extending between the sides of housing 138 and having a central aperture 162, is adapted to support a ratchet-pawl 164. The aperture 162 and the pawl 164 form a cross-head bearing and compensate for the angularity due to the pivoting of pawl 164 about pivot 160. The lower extremity of the pawl 164 is provided with a bifurcated portion 165 adapted to straddle the friction wheel 154 and to engage the teeth on ratchets 158. A collar 166 is fixed to the upper extremity of the shaft 160 and is adapted to limit its downward sliding motion. Another collar 168 is slidingly mounted on the shaft 164 below the pivot shaft 160, and it cooperates with another collar 170 and a spring 172 positioned between the two for resiliently urging the pawl 164 into engagement with the ratchet teeth of ratchets 158, and still permitting sliding of said pawl relative to its pivot 160 during its oscillatory movement. A drawbar 174 is

connected to an intermediate point of the pawl 164, and extends through an elongated slot 177 in the one side of the housing 138. The draw-bar 174 extends to, and between the conduits 132 and 118, passing within the handle 110, and is attached to one arm of a pivotally mounted bell-crank lever 176. The other arm of the bell-crank lever is connected with a link 178 extending through the side wall of the handle 110 and in spaced relation to the vertically aligned conduits 132 and 118. The link 178 is adapted to be connected to one side of the hand lever L'. In order to insure the return of pawl 164 to its initial position, and also to take up the lost motion within the connections between elements 120 and 116, a spring 180 is connected between the bell-crank lever 176 and the handle 110.

The lost motion connection between the stem 116 and the head 120 permits feeding the desired length of the wire into the pre-heat flames during the initial movement of hand lever L' without the oxygen stream being turned on, and continued operation of lever L' turns on the oxygen jet. This arrangement avoids the slight additional feeding of wire into the pre-heat flames, characteristic of the device shown in Fig. 1, when the oxygen jet is turned on.

From the foregoing description it will be evident that we have provided a speedier and more economical method of performing a cutting, deseaming, flame-machining or similar operation on a ferrous metal body. Preferably, the heating medium or flame used is of insufficient heating intensity to quickly heat to its oxygen ignition temperature that area on the surface of the metal body where the operation is to begin but such intensity is sufficient to continue the operation satisfactorily after the same has been started. The small amount of ferrous metal, such as a short length of wire fusible by the heating medium and combustible in oxygen, is introduced into the heating flame only during starting and, when said wire has been fused, the stream of oxygen is turned on and oxidizes such fused metal in its path and adjacent the pre-heated area on the body. Such oxidation of said wire liberates enough additional heat adjacent said area, and sufficiently supplements the heat already applied by said flame to said area, to very quickly raise to its oxygen ignition temperature at least that part of said area against which the oxygen stream is directed, thus considerably accelerating the starting of the operation. To complete the operation, the heating flame and the adjoining oxygen stream are immediately moved in unison relatively to the metal body and substantially parallel to the surface thereof to direct said flame and said stream against successive areas of said surface without, however, changing the intensity of the heating flame and without introducing additional wire into said flame during such relative movement.

While the principles of the invention have been illustrated in connection with a deseaming torch for conditioning surfaces of oxidizable steel bodies, it is to be understood that they may be applied with equal facility to a cutting torch for severing such steel bodies or to a machine embodying a bank of flame-machining nozzles for conditioning surfaces of such steel bodies.

What is claimed is:

1. A method of performing a cutting, deseaming, flame-machining or similar operation along a surface of an oxidizable steel body which com-

prises directing a heating flame against an area on said surface at a point where said operation is to begin, to heat said area; said heating flame being of insufficient intensity to quickly heat said area to its oxygen ignition temperature; introducing metal, fusible by said flame and combustible in oxygen, into said flame at a point adjacent such heated area; directing a jet of oxidizing gas against a part of said heated area and also against such fusible and combustible metal, after the latter has been raised to at least its ignition temperature by said flame, to oxidize such introduced metal adjacent said area so that the heat liberated by such oxidation supplements the heat applied to said area by said flame and quickly raises to an ignition temperature at least the part of said area against which said jet is directed; and thereupon moving said flame and said jet in unison relatively to said body and in a direction substantially parallel to said surface while directing both said flame and said jet against successive areas of said surface.

2. A method of performing a cutting, deseaming, flame-machining or similar operation along a surface of an oxidizable steel body which comprises directing a heating flame against an area on said surface at a point where said operation is to begin, to heat said area; introducing metal, fusible by said flame and combustible in oxygen, into said flame at a point adjacent such heated area; said fusible and combustible metal being a portion of a ferrous metal wire; directing a jet of oxidizing gas against a part of said heated area and also against such fusible and combustible metal, after the latter has been raised to at least its ignition temperature by said flame, to oxidize such introduced metal adjacent said area so that the heat liberated by such oxidation supplements the heat applied to said area by said flame and quickly raises to an ignition temperature at least the part of said area against which said jet is directed; said oxidizing gas being oxygen; said heating flame at the beginning of and throughout said operation, being of insufficient intensity by itself to quickly raise to an ignition temperature the part of said area against which such oxygen jet is directed; and the heat liberated by the oxidation of said portion of wire being sufficient to supplement the heat applied to said area by said flame at the beginning of said operation to very quickly raise to an ignition temperature said part of said area against which said oxygen jet is directed, and thereupon moving said flame and said jet in unison relatively to said body and in a direction substantially parallel to said surface while directing both said flame and said jet against successive areas of said surface.

3. A method of performing a cutting, deseaming, flame-machining or similar operation on an oxidizable steel body which comprises directing a heating medium against an area of the surface of said body at a point where said operation is to begin, to heat said area; said heating medium being of insufficient intensity to quickly heat said area to its oxygen ignition temperature; melting a small amount of metal, combustible in oxygen, and depositing such molten metal onto such heated area; directing a stream of oxidizing gas against a portion of said heated area and also against such deposited metal to oxidize the latter and thereby sufficiently supplement the heat applied by said heating medium to said area to quickly raise at least said portion of said area to its ignition temperature; and thereupon mov-

ing said stream of oxidizing gas relatively to said body and in a direction substantially parallel to the surface of said body.

4. A method of performing a cutting, deseaming, flame-machining or similar operation on an oxidizable steel body which comprises directing a heating flame against an area of the surface of said body at a point where said operation is to begin, to heat said area; melting a small amount 10 of metal, combustible in oxygen, and depositing such molten metal onto such heated area, said small amount of metal being a portion of a ferrous metal wire; directing a stream of oxidizing gas against a portion of said heated area and also 15 against such deposited metal to oxidize the latter and thereby sufficiently supplement the heat applied by said heating flame to said area to quickly raise at least said portion of said area to its ignition temperature; and thereupon moving said 20 heating flame and said stream of oxidizing gas in unison relatively to said body and in a direction substantially parallel to the surface of said body, said portion of wire being introduced into and melted by said flame only during the beginning 25 of said operation.

5. A method of performing a cutting, deseaming, flame-machining or similar operation on an oxidizable steel body as claimed in claim 3, in which said stream of oxidizing gas is an oxygen 30 jet adjoining said flame; said small amount of metal is a portion of a ferrous metal wire; said portion of wire is introduced into and melted by said flame above said surface and prior to such relative movement; and said oxygen jet impinges 35 against at least some of such molten metal above said surface.

6. A method of performing a cutting, deseaming, flame-machining or similar operation on an oxidizable steel body which comprises directing a 40 heating medium against an area of the surface of said body where said operation is to begin, said heating medium being of insufficient intensity to quickly heat said area to its oxygen ignition temperature; feeding into said medium adjacent said 45 area so heated, only a small quantity of ferrous metal fusible by said medium and combustible in oxygen; discontinuing the feeding of such fusible and combustible metal after said small quantity has been fed into said medium; immedi- 50 ately after such small quantity of metal has been fused by said medium, directing a stream of oxidizing gas against such heated area and also against such fused metal to oxidize the latter adjacent said area and thereby liberate enough 55 additional heat, supplementing the heat applied by said heating medium, to quickly raise to its ignition temperature at least that part of said area against which said stream of oxidizing gas is directed; and thereupon moving said heating 60 medium and such oxidizing gas stream in unison relatively to said body without feeding fusible and combustible metal into said medium or said stream during such relative movement.

7. A method of performing a cutting, deseaming, flame-machining or similar operation along a surface of an oxidizable steel body which comprises directing a gaseous heating flame against 65 an area of said surface at a point where said

operation is to begin, said flame being only of sufficient intensity to heat said area to a temperature lower than its oxygen ignition temperature; introducing, into said flame adjacent said area, a short length of ferrous metal fusible by 5 said flame and combustible in oxygen; after said short length of metal has been fused by said flame, directing a jet of oxygen against such heated area and also against such fused metal to oxidize the latter adjacent said area and thereby liberate enough additional heat, supplementing the heat applied to said area by said flame, to raise to its oxygen ignition temperature at least that part of said area against which said oxygen jet is directed; and thereupon moving said 10 flame and said jet in unison relatively to said body and in a direction substantially parallel to 15 said surface.

8. A method of performing a cutting, deseaming, flame machining, or similar operation on an oxidizable steel body, which comprises directing a heating flame against an area of a surface of said body at a place where said operation is to begin; heating to at least its ignition temperature a small quantity of metal that is combustible in 20 an oxidizing gas and depositing such combustible metal, so heated, adjacent to such heated area; directing a stream of oxidizing gas against a portion of said heated area and also against such heated combustible metal to burn the latter adjacent said area and thereby supplement the heat applied to said area by said heating flame, to quickly raise at least a portion of said area to its ignition temperature; and thereupon moving said 25 heating flame and said stream of oxidizing gas 30 in unison relatively to said body and in a direction substantially parallel to said surface of said body.

9. A method as defined in claim 8 in which said small quantity of combustible metal is heated to its ignition temperature and deposited on said heated area only before starting the movement of the flame and the stream of oxidizing in unison relatively to said body, and in a direction 35 substantially parallel to said surface of the body. 40

10. A method of performing a cutting, deseaming, flame machining, or similar operation on an oxidizable steel body, which comprises directing a heating flame against an area of the surface of said body at a place where said operation is to 45 begin; heating to at least its ignition temperature a small quantity of metal that is combustible in an oxidizing gas and depositing such combustible metal, so heated, adjacent to such heated area, said small quantity of metal being a 50 portion of a wire; directing a stream of oxidizing gas against a portion of said heated area and also against such heated combustible metal to burn the latter adjacent said area and thereby 55 supplement the heat applied to said area by said heating flame, to quickly raise at least a portion of said area to its ignition temperature; and thereupon moving said heating flame and said stream of oxidizing gas in unison relatively to 60 said body and in a direction substantially parallel to the surface of said body.

CERTIFICATE OF CORRECTION.

Patent No. 2,205,890.

June 25, 1940.

WILLIAM BRYCE NICHOLSON, ET AL.

It is hereby certified that error appears in the printed specification of the above numbered patent requiring correction as follows: Page 2, second column, line 31, for "if" read --of--; page 7, second column, line 43, claim 9, after "oxidizing" insert the word --gas--; and that the said Letters Patent should be read with this correction therein that the same may conform to the record of the case in the Patent Office.

Signed and sealed this 13th day of August, A. D. 1940.

(Seal)

Henry Van Arsdale,
Acting Commissioner of Patents.
